UNITED STATES PATENT OFFICE.

ALBERT S. HOWELL, OF CHICAGO, ILLINOIS, ASSIGNOR TO BELL & HOWELL COMPANY,
OF CHICAGO, ILLINOIS, A CORPORATION OF ILLINOIS.

APPARATUS FOR PERFORATING CINEMATOGRAPHIC FILMS.

1,291,524.

Specification of Letters Patent. Patented Jan. 14, 1919.

Application filed March 2, 1917. Serial No. 152,009.

To all whom it may concern:

Be it known that I, ALBERT S. HOWELL, a citizen of the United States, and resident of Chicago, in the county of Cook and State of Illinois, have invented certain new and useful Improvements in Apparatus for Perforating Cinematographic Films, of which the following is a specification.

My invention relates to apparatus for 10 perforating the margins of cinematographic film, and more particularly to an apparatus of this character that is capable of feeding the film, for perforating the same, and for discharging and rewinding the film after 15 the perforating operation.

One of the objects of my invention is the provision of a machine of this character that is adapted to perform all of its 20 functions in an automatic manner in order that the attention of the operator is unnecessary after the device has been started.

Another object of my invention is the provision of a film perforating machine that will punch the marginal perforations with 25 minute accuracy and at the same time perform this operation or function in a relatively rapid manner.

Further objects of my invention comprise the construction of a perforating machine 30 for motion picture film that is compact in construction and efficient in its operation in handling and operating upon the film, and also the provision of means whereby the movement of the ram, which carries the perforators, may be adjusted. And a further 35 object of my invention is the provision of a holder and stripper that is adapted to retain the film during the punching operation and coöperate in the removal of the same from the dies immediately thereafter.

I have also provided a novel shuttle mechanism and pilots that are together adapted to accurately move the film longitudinally and position the same immediately prior to the punching operation.

Further objects of my invention will be obvious after an understanding of my invention is had from the following description. I prefer to accomplish the divers objects of my invention in substantially the manner and by substantially the means hereinafter fully described and as more particularly pointed out in the claims, reference being had to the accompanying draw-

ings forming a part of this specification, in 55 which—

Figure 1 is a longitudinal front elevation of my perforating machine for cinematographic film.

Fig. 2 is a vertical transverse section on 60 line 2—2 of Fig. 1 looking in the direction of the arrows, the lower portion of the ram and the discharge end of the carriage or bed being illustrated in end elevation.

Fig. 3 is an enlarged fragmentary view 65 of the shuttle and stripper mechanism, together with the operating levers, the upper portion of the apparatus being removed for clearness.

Fig. 4 is a top plan of the bed or carriage, including the guides through which the cinematographic film is adapted to move. 70

Fig. 5 is a fragmentary view of a portion of the mechanism shown in Fig 2 and in 75 enlarged detail.

Fig. 6 is a perspective view of the shuttle for moving the film.

Fig. 7 is a perspective detail of the block employed in conjunction with the shuttle (Fig. 6) for longitudinally reciprocating the latter. 80

Figs. 8 and 9 are, respectively, plan and side views of the stripper plate.

Fig. 10 is an enlarged longitudinal section of the stripper plate. 85

Fig. 11 is a vertical longitudinal section of the means for actuating the film spools.

Fig. 12 is a rear elevation of the ram and link, together with the means for adjusting the same. 90

Figs. 13, 14, 15 and 16 are fragmental diagrammatic views showing the shuttle, pilots, punches and stripper in different relations assumed in their cycle of operation.

Referring to the drawings, it will be observed that my invention preferably comprises a suitable standard A, upon the upper end whereof is mounted a table B that is adapted to support the bed or carriage and the guideways for the film and said table 100 is provided with a segmental upright arm C. The upper end of the arm C terminates in a rectangularly shaped slideway or housing D in which the ram is adapted to reciprocate, and intermediate this housing D said 105 arm is provided with bearings for divers elements of the mechanism as will herein-after more fully appear.

Mounted upon opposite sides of the housing D, adjacent the lower end thereof, are laterally disposed tubular brackets 20, 21, the outer ends of which are preferably provided with upright brackets 22 and 23, respectively. Suitable bearings are provided in the upper ends of brackets 22 and 23, and arbors 24 and 25, respectively, are mounted therein so as to journal film spools thereon 10 and the usual retaining disks 26 are secured thereon to guide and keep the film on the film spools in compact form.

The roll of film is placed upon arbor 24 and threaded around an idle roller or spool 15 27 journaled upon the end of arm 20 and thence passes over a larger flanged roller 28 mounted upon a spindle 29, upon the adjacent end of arm 20, and is retained thereon throughout a major portion of the circumference of said roller 28 by a presser roller 30. The roller 30 is journaled in the movable end of a spring pressed arm 31 pivoted upon a lateral bracket 32 projecting from the adjacent end of the arm 20. Upon leaving the spool 28 and roller 30, the film is looped and passes over a guide roller 30^a and into the receiving end of the bed or carriage of the machine, illustrated in detail in Fig. 4 of the drawings.

30 The bed or carriage is of such construction that the film will travel therethrough in a manner so that the emulsion surface thereof which is uppermost will not be engaged or come in contact with any of the elements of 35 the carriage at the portions that afterward receive the pictures, and thus avoids the liability of spoiling or marring the sensitized surface. The specific details of the bed and carriage form the basis of a co-pending 40 application executed by me even date here-with and filed March 2nd, 1917, Serial No. 152,010, and, therefore, does not require a detailed description. However, it will be observed that the bed or carriage comprises 45 longitudinally disposed parallel blocks 33 that are secured to the upper surface of an adjustable wing B¹ of the table B, and are provided with a plurality of small rollers 34. There are preferably three rows of these 50 rollers,—a center row which supports the central portion of the film and two outer rows that carry the marginal edges of the film, the latter or outer rows being so disposed that they will engage the film at or 55 outside the line or part in which the perforations are to be made. Above the base blocks 33, at one side of the film path, is removably mounted a guide plate 35 that has a row of rollers 36 journaled adjacent the edge there- 60 of and is adapted to guide and position the film with respect to the perforating dies. The rollers 36 register with and are above the adjacent row of rollers 34. A removable yielding guide plate 37 is mounted upon the 65 opposite side of the bed or carriage and

likewise is provided with a row of rollers 38 that register with the rollers in the base plates immediately below the same. The spring 39 normally keeps said plate 37 pressed toward the film in a yielding manner and is adapted in this way to take care of any unevenness in the adjacent edge of the film due to transverse shrinkage of the emulsion. It will be seen that all these rollers co-act to present the film to the punches in a horizontal plane and flat and even. Arms 40 and 41 project, respectively, from the ends of guide plates 35 and 37 and extend upon opposite sides of the lower perforating die to form a film channel across 70 the same and guide the edge of the film while adjacent the dies. The guideway for the discharging end of the table is constructed similarly to that just described and comprises base blocks 42 having rollers 43 journaled between the same and are secured upon a wing B² of the table. A removable skeleton plate 44 is adapted to be slid into suitable guide passages above the base blocks and is provided with marginal rollers 45 90 that engage the upper surface of the edge of the film after it has passed from the punches. A latch 46 is adapted to removably lock this skeleton plate 44 in its guideway and the rollers of said skeleton plate register with the marginal rollers journaled between the outer base blocks 42. It will thus be seen that a continuous guide is provided for the film from the receiving end past the dies and out the discharge end of the table.

100 After the film has passed from the discharging end of the table it is looped down slightly over a guide roller 45^a and then drawn upwardly through a suitable film cleaning device E, the details of which are 105 fully set forth in an application executed by me November 16, 1916, and filed November 27, 1916, Serial No. 133,768, for a device for cleaning film. The cleaning device is carried upon pendant member 47 projecting 110 downwardly from the outer end of the arm 21. The film is thoroughly cleaned of any foreign matter by the cleaning device E and thence passes upwardly over a sprocket 48, around an idle roller 49, and is rewound 115 upon the spool carried by arbor 25. A presser roller 50 keeps the film firmly pressed upon the sprocket 48 and is similar in construction to the presser roller 30 upon the opposite end of the machine. The spool upon 120 arbor 25 is driven by means of a drive pulley 51 journaled upon the end of arm 21 and a belt 52 that connects said pulley 51 with a pulley 53 upon the spool on arbor 25.

125 Intermediate its ends the arm C of the table is transversely bored at 54 and in its opposite ends said bore is provided with anti-frictional ball bearings 55 and 56 for journaling the main drive shaft 56. The outer end of shaft 56 extends beyond its 130

bearings and has a drive pulley 58 secured thereon that derives its motion from a suitable motor by means of a belt or otherwise. Intermediate its bearings the drive shaft 57 is provided with a worm gear 59 for actuating suitable mechanism that drives the pulleys 28, 48 and 51. The oppositely disposed tubular arms 20 and 21 as shown in Fig. 11 of the drawings are each provided adjacent their inner and outer ends with anti-frictional bearings 60 for suitable horizontally disposed transmission shafts 61 and 62, respectively. The outer ends of these shafts are respectively provided with spiral gears 63 and 64 that mesh with spiral gears 65 and 66 carried upon the spindles X and 29, respectively. It will be seen that the rotation of the drive shaft 57 transmits its motion to a spiral gear 67 connecting the shafts 61 and 62, which in turn transmit the motion to the spiral gears upon the ends of the respective transmission shafts and drive the respective pulleys for feeding the film to the carriage and withdrawing it therefrom.

The slideway or housing D is of rectangular shape and substantially U-shape in horizontal section, a facing plate or closer 68 being secured to the outer vertical edges of the horizontal or lateral members to provide a suitable guideway 69 wherein the reciprocable ram 70 is mounted. The rear surface of the ram, nearest the shaft 57, is preferably provided with a recess 71 of dumb-bell outline, in which the operating element is conveniently set. This element comprises a link 72, the ends whereof are lobe-shape or circular, so as to provide seats to receive anti-frictional roller bearings 73 and 74. A crank pin 75 mounted eccentrically upon and extended from the adjacent end of shaft 57 engages the link in its bearing at its lower end, and the upper end of the link is connected to the ram by an adjusting member 76, having a lateral eccentric stud 77 projecting from the end thereof adjacent the upper end of the link. This adjusting member 76 is preferably cylindrical in shape as shown in detail in Fig. 2 of the drawings, and is provided with a concentric recess or groove 78 into which the lower end of a pin 79 fits. A set screw 80 is tapped into the upper end of the ram so that its lower end engages the pin 79 and locks the same together with adjusting element 76 in divers positions and headed nut 81 is mounted upon the outer end of the element 76 and access is had to this nut by means of an aperture 82 in the facing plate 68. It will be observed that by releasing the set screw 80 the adjusting element may be rotated by means of the nut 81, thereby raising or lowering the eccentric stud 77 on the opposite end thereof which thus raises and lowers the ram with relation to the lower die members of the perforator and alters the ini-

tial position of the throw of the ram with respect to the lower die.

The lower end or head 83 of the ram is preferably constructed to receive the pilots and the upper perforating members in any suitable manner and is provided with extensions 84 between which the said pilots and perforators are mounted. Suitable retaining plates 85 are secured to the opposite sides of these extensions 84 to form a box 75 or tool holder in which these pilots and perforators are mounted. The pilots comprise a plurality of vertically disposed parallel pins 86, arranged four upon each side, for the purpose of engaging the film adjacent the margins and are adapted to enter the perforations previously made by the punches. The punching members comprise a plurality of blunt pins or entering die members 87 arranged in longitudinal alinement with the pilots 86, preferably four in number, for each margin of the film. Taken together the pilots and punches provide eight parallel members that are moved simultaneously downward toward and engage the film 90 that has momentarily been stopped to be perforated. After the machine has been started the pilots will engage the four perforations made by the previous operation of the dies and are longer than the punches so that they will engage the film and position it with accuracy when the punches which are simultaneously approaching the film engage the latter and perforate the same in the correct position. Opposing the ram, and the pilots and punches, is the lower die member 88, across which the film is adapted to be guided by the carriage and bed structure heretofore described, and which preferably comprises a rectangularly shaped plate 105 (Fig. 4), the longitudinal and transverse edges whereof are fitted snugly between the guide plates and guide arms of said carriage. The longitudinal edges of this die 88 are provided with marginal rows of recesses or openings 89, preferably eight upon each side to receive the pilots and the punches that coöperate therewith.

In order to strip the film from the pilots and punches when the same are being withdrawn from the film, I have provided a suitable stripper plate 90, shown in detail in Figs. 8, 9 and 10 of the drawings. This plate, as will be observed, is of substantially rectangular shape and its outer portion is 115 preferably provided with longitudinal ribs 91, between which are two rows of apertures 92 through which the pilots and punches pass. The under surface of this stripper plate is preferably provided with transverse 120 ridges 93 that are disposed in vertical alinement with the rows of apertures above mentioned, so that the plate will engage the film only at its margins and adjacent the path of the perforations, so that it will not mar or 130

injure the sensitized emulsified surface thereof. The stripper plate is mounted upon the end of the irregularly shaped bell-crank lever journaled on a stud 94 projecting from one side of the upright segmental arm C. The horizontal member 95 of this bell crank projects forwardly in an oblique manner toward the ram and is then deflected slightly so that its end portion lies parallel with the line of movement of the film where it is provided with a rectangularly shaped embossment 96 to the under surface whereof the stripper plate 90 is secured. The upright member 97 of this bell crank extends upwardly slightly oblique to a true vertical plane and is provided with a base 98 in its upper end that is bored horizontally to receive a suitable spindle 99 for a roller 100 that is journaled on the end thereof. The roller 100 is adapted to ride in a peripheral cam slot 101 in the edge of a cam disk 102 journaled upon the extended end of the drive shaft 57. The cam slot 101 is so constructed that the bell crank is adapted to raise the stripper plate 90 the moment the film is moved by the shuttle mechanism and is lowered immediately the movement of the film is stopped. The cam slot, for convenience, is made in the bottom of another cam slot 103, the purpose of which will hereinafter appear.

The means for moving the film strip after it has been perforated preferably comprises a suitable reciprocable shuttle that is provided with means for engaging the perforations and withdrawing the film from the dies, after which the shuttle is lowered out of engagement with the film and is returned to its initial position to engage the next set of perforations. This film actuating member comprises a shuttle that consists of an elongated sleeve 110, the details whereof are illustrated in the perspective view (Fig. 6) of the drawings. The sleeve 110 is bored axially so that it may be mounted to reciprocate longitudinally upon an elongated stud 111 projecting from the adjacent end of a bell crank and is disposed parallel to the path of movement of the film, and extends under the perforating dies into a suitable cylindrical chamber 112 made in the table below the bed. Intermediate its ends this sleeve is provided with an upstanding T-shaped bracket 113, from the upper surface of each of the arms whereof project a plurality (preferably four) of picks or fingers 114. The T-shape member 113 is provided with a slot or guideway 115 extending transversely of the axis of the sleeve 110 and open at the top and sides, and a suitable actuating guide block 116 is disposed therein. The guide block just mentioned is provided with downwardly projecting end extensions 117 that engage the flat vertical surfaces 118 of the shuttle so that said block may be raised

and lowered in a true vertical plane in the guideway 115. A suitable bearing is bored through the block longitudinally (or transverse to the axis of sleeve 110) to receive a stud 119 mounted upon the adjacent end of a vibratory crank arm 120. The crank arm 120 depends from the inner end of a rock shaft 121 that is disposed in horizontal bearings 122 in the arm C of the apparatus. The opposite or rear end of rock shaft 121 extends beyond its bearing and has a suitable cam arm 123 secured thereto so that the upper end of the latter will be disposed adjacent the horizontal plane of the axis of drive shaft 57. A transverse or lateral spindle is mounted in the upper end of cam arm 123 and carries a roller 124 upon its end nearest the cam disk 102 heretofore mentioned, and is adapted to ride in and be guided by the cam slot 125 made in the outer face of this cam disk. The cam slot 125 is so plotted that the shaft 121 is rocked sufficiently to cause the crank 120 to vibrate, thereby reciprocating the block 116 and moving the shuttle longitudinally upon the stud 111. This reciprocation is preferably of a length corresponding to the distances between four successive perforations in the film, it being customary to provide four perforations to each margin of a picture that is afterward developed upon the sensitized film, and this movement is sufficient to shift the film so that the perforations that have just been made by the punches 87 will be moved in position to receive the pilots 86 which position the film for the next succeeding set of perforations. It will be observed that the horizontal reciprocation of the shuttle is caused by a somewhat segmental movement of the block 116 sliding vertically in the guideway 115 of the shuttle, but the upper edge of the block does not reach a plane which would rise above the path of the film and interfere with the movement of the latter.

In order to impart to the film actuating shuttle an up or down movement at each end of its horizontal reciprocation, the stud 111 is preferably carried upon the adjacent end of a bell crank pivoted at its elbow upon a suitable stud 126 projecting from the side of arm C of the apparatus. The horizontally disposed arm 127 of this bell crank carries the stud 111 while the vertical arm 128 extends obliquely upward and terminates in substantially the horizontal plane of the axis of drive shaft 57. A suitable roller 129 is mounted upon a lateral stud 130 in an embossment 131 at the upper end of arm 128, and this roller 129 fits into the outer or wider slot 103 heretofore mentioned, so that the arm 128 is vibrated laterally at its upper end, thereby imparting a vertical vibration to the outer end of its horizontal arm 127 which carries a stud 111.

It will be observed that the rock shaft 130

121 and its associated members 120 and 123 are so synchronized or timed with respect to the movement of the stud 111 that the latter is raised at the innermost end of the movement of the shuttle and lowered at the outermost end of the movement of said shuttle, thereby inserting the fingers 114 of the shuttle into the film adjacent the dies and withdrawing said fingers at the moment the punches and pilots are started in their downward movement. The stripper plate 90 is likewise timed to be elevated immediately the punches have been withdrawn and the fingers have begun their engagement with the film and is lowered into engagement with the film immediately prior to the withdrawal of the shuttle fingers from the film so that at all times during the punching operation, (in other words, when the punches and pilots are moved down and up,) the stripper plate engages the film and simultaneously with the insertion of the shuttle fingers the stripper plate releases its hold upon the film and vice versa.

I have in the above specification described divers details in connection with my invention but it will be obvious to others skilled in the art to which this invention pertains that modifications, refinements and changes may be made thereto without materially departing from the spirit of my invention. I desire it understood that I do not limit myself to the precise construction herein described and shown, the drawings being in a sense diagrammatic of the device and such obvious changes as may be made are contemplated as included within the scope of my invention as expressed in the appended claims.

40 What I claim as new is:—

1. In an apparatus for perforating film, coöperating perforating dies, a shuttle adapted to engage the perforations in the film and move said film past said dies consisting of a reciprocable member, an oscillatory spindle upon which said member is mounted, and means for causing the latter to reciprocate upon said spindle.

2. In an apparatus for perforating film, coöperating perforating dies, an oscillatory arm, a shuttle adapted to move the film past said dies consisting of an elongated sleeve slidably mounted on said arm, a lateral member projecting from said sleeve, fingers on said lateral member adapted to enter the perforations in the film, and means for reciprocating said sleeve on said arm longitudinally with respect to the path of movement of the film.

60 3. In an apparatus for perforating film, coöperating perforating dies, a shuttle adapted to move the film past said dies consisting of a sleeve, members carried thereby adapted to engage the perforations in the film, means for reciprocating said sleeve,

and an oscillatory spindle upon which said sleeve is mounted and movable longitudinally.

4. In an apparatus for perforating film, coöperating perforating dies, a shuttle adapted to move the film past said dies consisting of a sleeve, members carried thereby adapted to engage the perforations in the film, a spindle upon which said sleeve is movable longitudinally, means for reciprocating said sleeve longitudinally upon said spindle, and a rocker arm upon which said spindle is mounted for vibrating the latter and the elements carried thereon whereby the film-engaging members are moved into and out of engagement with the perforations in the film.

5. In an apparatus for perforating film, coöperating perforating dies, a shuttle adapted to move the film past said dies consisting of a sleeve, members carried thereby adapted to engage the perforations in the film, a spindle upon which said sleeve is movable longitudinally, means for reciprocating said sleeve longitudinally upon said spindle, a rocker arm upon which said spindle is mounted for vibrating the latter and the elements carried thereon whereby the film-engaging members are moved into and out of engagement with the perforations in the film, and a device common to both of said actuating means for operating the same.

6. In an apparatus for perforating film, coöperating perforating dies, and a shuttle adapted to move the film with respect to said dies consisting of a sleeve provided with a lateral member, fingers upon said member adapted to engage perforations in the film, a vibratory lever having slidable connection with and adapted to reciprocate said sleeve longitudinally, a spindle upon which said sleeve is movably mounted, a second vibratory lever upon which said spindle is mounted, and means common to both levers for actuating the same.

7. In an apparatus for perforating film, coöperating perforating dies, a stripper coacting with said dies, a vibratory lever on which the stripper is carried, a shuttle provided with members adapted to engage perforations in the film, a lever adapted to reciprocate said shuttle longitudinally with respect to the path of movement of the film, a lever adapted to move said shuttle fingers into and out of engagement with the film perforations, and means common to all of said levers for actuating the same.

8. In an apparatus for perforating film, coöperating perforating dies, a device adapted to engage the perforations in said film and move the film past said dies, a lever pivoted intermediate its ends and upon one vibratory end whereof said device is slidably carried whereby said lever is adapted to move said device into and out of engage-

- ment with the film, a second lever pivoted intermediate its ends adapted to reciprocate said device upon said first mentioned lever longitudinally with respect to the path of 5 movement of the film, and means common to both of said levers for actuating the same.
9. In an apparatus for perforating film, coöperating perforating dies, a reciprocable device adapted to move the film past said 10 dies, means adapted to move said device into and out of engagement with the perforations in the film, a stripper, a lever upon which said stripper is mounted, and a cam-disk common to said elements for actuating 15 the same.
10. In an apparatus for perforating film, coöperating perforating dies, a device adapted to move the film past said dies, a bell-crank lever upon which said device is mounted 20 and which is adapted to move the same into and out of engagement with the perforations in the film, a vibratory member independent of said lever adapted to move said device upon said bell-crank lever, and a cam-disk common to said lever and vibratory device 25 for actuating the same.
11. In an apparatus for perforating film, coöperating perforating dies, a device adapted to engage the perforations in the film and 30 move the film past said dies, a vertically vibratory member upon which said device is mounted, a horizontally vibratory member adapted to move said device longitudinally with respect to the path of the film and independently of said vertically vibratory member, a stripper, a vertically vibratory device upon which said stripper is mounted, and a cam-disk common to said vibratory members and said vibratory device for im- 35 parting motion thereto.
12. An apparatus for perforating motion picture film comprising coöperating perforating dies and means adapted to move the film past said dies consisting of a shuttle 40 adapted to enter and be withdrawn from the perforations in the film, a lever adapted to move said shuttle into and out of engagement with the film and provided with a spindle upon which said shuttle is mounted 45 to move longitudinally thereon, and means for moving the said shuttle longitudinally upon said spindle independently of the movement of said lever.
13. An apparatus for perforating motion picture film comprising coöperating perforating dies, a vertically vibratory spindle, 50 a shuttle mounted on and longitudinally movable upon said spindle and adapted to engage and disengage the perforations in the film, and means for causing a longitudinal reciprocation of said shuttle upon said spindle.
14. An apparatus for perforating motion picture film comprising coöperating perforating dies, a horizontally disposed vertically vibratory spindle, a shuttle mounted and longitudinally movable upon said spindle and adapted through the movement of said spindle to engage and disengage the perforations in the film, and means for causing a longitudinal reciprocation of said shuttle upon said spindle.
15. An apparatus for perforating motion picture film comprising coöperating perforating dies, a bell-crank the vibratory end 75 whereof is provided with a horizontally disposed vertically vibratory spindle, a shuttle mounted on said spindle and adapted to be moved thereby into and out of engagement with the perforations in the film, and means adapted to move said shuttle longitudinally of said spindle independently of the movement of the latter.
16. In an apparatus for perforating film, coöperating perforating dies, a shuttle 80 adapted to engage the perforations in the film and move said film past said dies consisting of a reciprocable member, an oscillatory spindle upon which said member is movably mounted, and means slidably engaging the said member for causing the latter to reciprocate upon said spindle.
17. An apparatus for perforating motion picture film comprising coacting perforating dies, a stripper, a lever upon which said stripper is mounted, a shuttle adapted to engage the perforations in the film and move the film past said dies, a lever adapted to move said shuttle in one direction, a separate lever adapted to move the shuttle in a 90 direction at right-angles to its other path of movement, and a cam-disk common to all of said levers adapted to actuate the opposite ends thereof.
- Signed at Chicago, county of Cook, and 105 State of Illinois, this 27th day of February, 1917.
